UNITED STATES PATENT OFFICE.

FRANK WALDO HEWITT, OF ARLINGTON, MASSACHUSETTS, ASSIGNOR TO SIMPLEX ELECTRIC HEATING COMPANY, OF CAMBRIDGE, MASSACHUSETTS, A CORPORATION OF MASSACHUSETTS.

ELECTRIC HEATER.

1,238,727.

Specification of Letters Patent. Patented Aug. 28, 1917.

Application filed May 27, 1916. Serial No. 100,331.

To all whom it may concern:

Be it known that I, FRANK WALDO HEWITT, a citizen of the United States, and resident of Arlington, county of Middlesex, 5 and State of Massachusetts, have invented an Improvement in Electric Heaters, of which the following description, in connection with the accompanying drawings, is a specification, like letters on the drawings 10 representing like parts.

My present invention is an electrical heating device and the object of the invention is to improve and perfect such electrical heating devices.

15 In utilizing as expensive a heating element as electricity it is of great importance to conserve the energy and to supply as high a degree of heat as is possible, together with a system or apparatus which will insure 20 long life to the heater. Heretofore electric heaters in such devices as are commonly employed in domestic use have been built in two distinct ways. Either the heat generated in the heating element was transmitted 25 to the surface being heated, by conduction, or the heat was dissipated from the heat generating body by radiation.

The first of these methods involves a construction whereby the heat generated must 30 pass through a heat insulating substance to get to the part being heated. This is an unnatural path for heat to travel, and in order to force it to travel such a path there must be a substantial difference in temperature 35 between the heating element and the part being heated. This results in developing a high temperature on the element if the part being heated is brought to a temperature that is sufficiently hot for general utility 40 purposes, and is objectionable, rapidly deteriorating and oxidating the heating element.

The second system of heating by radiation from the heating element has heretofore 45 been used by supporting the heating element in a grooved member—this member being of electrically insulating material, and consequently of heat insulating material. The usual practice is to place a coiled wire in 50 the grooved member—thus permitting the heat to radiate, but only from a limited area of the coil. The inability to dissipate its heat freely on all sides results in the heater attaining a higher temperature than if the

material surrounding the coil were of a nature that would conduct the heat away as generated, and therefore this second method is also objectionable and unsatisfactory.

It is a principle of natural phenomena that as the temperature of a body increases 60 the heat dissipated from that body by means of radiation increases in a much larger ratio, so that when a body approaches a red heat it dissipates a very large percentage of its heat by radiation, and my present invention 65 takes advantage of this principle. Also I make use of the further principle whereby the heat thus radiated is quickly absorbed and conducted away, with the result that the temperature of the wire is relieved on 70 all sides, and very quickly after generated, thus insuring long life to the heating element.

In my system the heat generating element is practically surrounded closely on all sides 75 by heat conducting material, and the only obstruction to the flow of heat from this heat generating element to the part being heated is a very small space, which space is entirely free of obstruction by any physical 80 substance through practically the entire length of the coil.

As in practice the heating element is operating at a red heat or somewhat higher, as stated above, the natural way for it to 85 dissipate its heat under this condition is by radiation, consequently the coil as supported in my system is in a condition that is much more favorable to taking heat away quickly from the heating element than in either of 90 those above mentioned.

This permits the dissipation of heat from the element without its attaining an excessive temperature, and thus durability of the element is assisted. Inasmuch as the heat 95 conducting material is in very close proximity to the heating element, I am enabled to reduce the temperature difference between the heater and the part being heated, and to raise the heating surface of the heater 100 substantially to the same degree of heat as that of the heating element itself.

A further feature of the invention is in its mechanical arrangement to permit easy and simple assembly by unskilled labor, and 105 to result in a construction that is rigid and durable, and in no sense fragile.

In carrying out my invention I may uti-

lize a soft cast iron heater plate, which is an excellent heat conducting material and by arranging the heating wires in close thermo-proximity while still maintaining the 5 same electrically separated by a suitable air space, the cast iron will readily absorb the heat radiated from the wires and conduct said heat to the working surface of the heater. Thus the life of the resistance 10 wires is greatly increased by freeing themselves of heat, quickly, from every point, excepting at a minimum of supporting points. To support the heating element in position I prefer to use thin sheets of mica or the 15 like, slotted to receive the resistance wire or coil of wires and arranged transversely of the wires, so as to occupy a minimum amount of space and not interfere with the free heat radiation therefrom. I also arrange the heating wires, if in the form of coils as preferred, so that the continuity of the wire from one coil to another is unbroken, irrespective of the change in direction of the coils.

20 25 Further important advantages, features of the invention, details of construction and novel combinations will be hereinafter more fully pointed out and claimed.

Referring to the drawings illustrating a 30 preferred embodiment of the invention

Figure 1 is a view in perspective of the under-side of a grooved heating plate with the cover removed;

Fig. 2 is an enlarged fragmental cross- 35 sectional view of one edge of the heater;

Fig. 3 is a fragmentary view of the mica insulating and supporting arrangement;

Fig. 4 is a view of the arrangement at the 40 end of two adjacent coils, showing the continuity of the resistance wire from one coil to another;

Fig. 5 is a plan view of said coils and their connections at each end; and

Fig. 6 is a cross sectional, fragmentary 45 view of a heater and mica insulating supports in the groove construction with a plurality of heating coils.

It will be understood that I may utilize a heating plate of any desired size, shape 50 or contour, such as round, square or the like, the usual electrical heating device in stoves for domestic use being square or round, and I have illustrated my invention with a rectangular heater.

I form the heating device 1 of cast iron, with a smooth top 2 or utensil-receiving surface, which is the working surface of the heater and on which the article to be heated is placed. The under-side of the 55 heating device 1 is cast with a plurality of grooves 3 and alternating ribs 4 of suitable depth and diameter to receive the coils of the heating wires to be applied therein. I cut, cast or mill across the ribs 4 slots at 60 suitable points to receive the insulating ma-

terial, preferably mica, or the like, 6, arranged to support the coils 5 in predetermined position within the grooves 3. I prefer to leave the outer sides and ends of the heating device 1 rigid to impart strength 70 to the entire heater and prevent warping of the top plate or working surface 2. The ribs 4 also prevent such warping, but are somewhat weakened by the transverse slots to receive the insulating element 6. These 75 slots are of just sufficient width to receive the thin sheets 7 and 8 of mica, which may be forced or jammed therein. The mica sheets are fitted with cooperating grooves 9 in the top sheet 7 and 10 in the lower 80 strip 8, which grooves are of suitable depth and position to cooperate with each other in holding the heating coils 5 in desired position relatively to the depth of the grooves 3. Preferably I so arrange the mica 85 insulating supporting strips 7 and 8 that the heating coils 5 will be sustained almost at the extreme bottom of the grooves 3 and in as close thermo-proximity to the under-surface of the top 2 as can safely be attained 90 without said wires actually touching the cast iron. As the heat from the coils 5 is radiated in all directions, this construction enables the heating coil to be substantially surrounded by the heat conducting iron of 95 the top 2 and ribs 4, conserving all of such heat and further aiding the free dissipation of heat from the wires by the rapid absorption and conduction to the working surface 2. To still further conserve the heat radiated from the coils 5, which would otherwise escape from the open mouths of the grooves 3, I affix a cover 11, preferably of metal, over the under-side of the heating device 1, attaching the same thereto by 100 screws 12 at suitable points around the heater. I may also prefer to do the heat insulating packing by mineral wool or the like under the cover 11, and inclose the same by a thin metal sheet 14, illustrated in fragmentary form in Fig. 2, securing the latter by bolts 15 to a flange 16 on the heating device 1.

If desired, a plurality of heating coils may be fitted within the grooves 3 as indicated in Fig. 2 by the additional coils 17, in which construction an intermediate mica plate 18, having top and bottom slots 19 and 20 respectively, is provided, to cooperate with additional mica sheets 21 and 22 corresponding to the strips 7 and 8 of Fig. 3 to hold the heating coils 5 and 17 spaced from each other and from the ribs 4 and heating device 1.

It is very desirable that the continuity of 125 a resistance wire, such as the heating coils 5, should not be broken, even when a change of direction in the wire is necessary, the breaking of such wires and carrying the current through soldered joints over other 130

wires or different mechanical means, is expensive and an unsatisfactory construction. Such soldered joints are apt to break through constant temperature changes, because of the concentration of heat, prevent uniform flow of current, induce oxidation, and present a weak and unsatisfactory construction. I obviate these difficulties by having the coils connected by integral wires 23, see Figs. 4 and 5, which will lie in grooves 24, one at the bottom of the coils which it connects, as, for example, 25 and 26, and the other leading from the top of the adjacent coils which it connects, 27 and 28. This arrangement enables me to keep all the heating coils 5 in the same plane and yet connect them by the short portions 23 with the latter spaced apart and joining alternate coils. This also is advantageous in enabling the usual three heat construction of an electrical heater to be obtained, supplying two circuits through the heater, the circuits designated as A and B being capable of use single, in series or multiple, thus fulfilling the usual requirements for electrical stove use.

My improved electrical heater is capable of very easy assembling, without special fittings, screws, tools or skill. The plate 1 of cast iron or other desired heat-conducting material may be roughly cast to form, the slots milled out or cast for the insulating elements and then a lower mica strip 8 (or 22 when the form shown in Fig. 6 is utilized) is fitted within each of said slots, said strip being preferably equal in length to the width of the heater, the heating device 1 being inverted with the grooved side uppermost to facilitate this assembling. The end mica strips, shown in Fig. 4, also include the top member 29, intermediate strip 30 and lower strip 31, grooved as shown in said figure, the lowermost strip 31 being similarly positioned in the end slots. The heating coils 5 are then laid in position, resting on the slots 10 of the lower supporting mica strip 8, and the second or top member 7 being then forced into position as shown in Fig. 3, wedging with the member 8 into the slot cut therefor. Similar operation at the ends where the connecting sections 23 are to be fitted, is also performed, the wedging action of the insulating strips serving to hold the wires and said strips in assembled position. The bottom plate 11 is then fitted, and the packing 13 and cover 14 applied, the heating device 1 reversed with the top plate 2 uppermost and terminals 32 and 33 connected at the end of the circuits A and B respectively.

The electrical heater just described illustrating a preferred embodiment of the invention, is to be understood as being shown for illustrative purposes only and not to limit my invention thereto. The invention however, is

peculiarly applicable to the type of grooved heater herein shown and described, and enables each heating coil to be supported with a minimum of insulation, i. e., the thin edge of the mica strips, between the coils and the heat conducting material of the top 2.

My invention is further described and defined in the form of claims as follows:

1. An electrical heating device comprising a heat conducting plate formed with a plurality of parallel grooves and depending heat conducting portions of said plate, constituting the sides of the grooves, resistance coils suspended in each groove in substantially equal thermo-proximity to the sides and bottom of said groove, but electrically insulated therefrom by an air space, insulating supporting means for said coils at spaced intervals in each groove.

2. An electrical heating device comprising a heat conducting plate formed with a plurality of parallel grooves, resistance coils suspended in each groove in close thermo-proximity to the sides and bottom of said groove, but electrically insulated therefrom by an air space, and mechanical insulating supporting means wedging said wires against displacement longitudinally and spanning the grooves at spaced intervals and holding the resistance coils in said air-spaced relation.

3. An electrical heating device comprising a heat conducting plate formed with a plurality of parallel grooves, resistance coils suspended in each groove in close thermo-proximity to the sides and bottom of said groove, but electrically insulated therefrom by an air space, and slotted mica sheets secured to said plate and spanning said grooves constituting a mechanical insulating support for the resistance coils to hold them suspended in said grooves.

4. An electrical heating device, comprising a heat conducting support having a plurality of parallel grooves, a resistance element suspended in each groove and insulated by an air space from the support, and insulating means holding said resistance elements suspended in said grooves, said insulation being spaced longitudinally of the resistance elements and comprising thin overlapping mica sheets.

5. An electrical heating apparatus, comprising a heat conducting plate having a plurality of parallel grooves, a resistance element suspended in each groove, and insulating means holding said resistance elements in said grooves and air-spaced therefrom, said insulation consisting in a plurality of slotted strips spaced longitudinally of the resistance elements and interlocking with said resistance elements and with the sides of the walls forming the grooves to hold the resistance elements suspended in said grooves.

6. An electrical heating apparatus, comprising a heat conducting plate having a plurality of parallel grooves, a plurality of resistance elements in vertical alignment and spaced equally from the sides of each groove, and insulating means holding said resistance elements in said grooves and air-spaced therefrom and from each other, said insulation being spaced longitudinally of the resistance elements.

7. An electrical heating apparatus, including a heat conducting member formed with a smooth surface on one side and a plurality of grooves on the other side, each groove being adapted to receive a resistance element of slightly less diameter than the cross sectional area of said groove, means to hold the resistance element in each groove in close thermo-proximity to the sides and bottom of the groove, but electrically insulated therefrom by an air space and at spaced intervals by insulating means supported by the partitions forming said

grooves and adapted to engage the resistance element at spaced intervals.

8. An electrical heating apparatus, including a heat conducting member formed with a smooth surface on one side and a plurality of grooves on the other side, each groove being adapted to receive a resistance element, means to hold the resistance element in each groove in close thermo-proximity to the sides and bottom of the groove, but electrically insulated therefrom at spaced intervals by insulating means adapted to be wedged in transverse slots across the partitions forming said grooves and supporting the resistance elements at spaced intervals.

In testimony whereof, I have signed my name to this specification, in the presence of two subscribing witnesses.

FRANK WALDO HEWITT.
